HYDROCARBON BURNER

Merlin E. Palsgrove, Columbus, Ohio

Application March 20, 1940, Serial No. 324,994

8 Claims. (Cl. 158—91)

This invention relates to improvements in oil burners, and has particular reference to that type of oil burners in which the hydrocarbon oil is fed in a regulated manner into a trough arranged adjacent to a combustion chamber formed in the burner casing and, wherein, during the operation of the burner, oil introduced into the trough is vaporized and admixed with air to form a highly combustible mixture.

It is an object of this invention to provide a simple and efficient construction of parts in which the combustion of the oil is accomplished in a safe and effective manner, producing a stable rate of combustion which may be continuously maintained during operation of the burner.

It is another object to provide an oil burner especially adapted for use with water tanks or troughs employed for drinking purposes by live farm stock, the operation of the burner producing sufficient heat to maintain bodies of water used for such purposes at non-freezing temperatures.

A still further object is to improve and simplify the construction and operation of oil burners of the character set forth, so that such burners may be rendered comparatively easy and inexpensive to manufacture, reliable and efficient in use and convenient to manipulate and adjust.

For a further understanding of the invention, reference is to be had to the following description and the accompanying drawings, wherein:

Fig. 1 is a perspective view of an exterior of an oil burner formed in accordance with the present invention;

Fig. 2 is a vertical longitudinal sectional view taken through the burner;

Fig. 3 is a vertical transverse sectional view taken on the plane indicated by the line III—III of Fig. 2;

Fig. 4 is a perspective view of the adjustable apertured plate utilized by the present invention;

Fig. 5 is a similar view of the oil trough capillary screen;

Fig. 6 is a detail perspective view of one of the extension wires used in the oil-receiving trough of the burner.

Referring more particularly to the drawings, the numeral 1 designates the box-like casing of my improved burner. Preferably, this casing is in the form of a metallic casting and embodies transversely spaced, parallel, vertical side walls 2, a bottom wall 3 and front and rear end walls 4 and 5 respectively. Internally, the casing 1 is formed with a vertical transversely extending

wall 6 which, in connection with the wall 5 and the bottom 3, forms a combustion chamber 7.

Arranged within the chamber 7 and extending from the walls 2 and 5 of the casing 1 is a ledge 8 shaped to provide an oil-receiving trough or well 9. Liquid oil is introduced in regulated quantities into the bottom of the well 9 and is there subjected to sufficient heat to effect its vaporization or hydroxylation with atmospheric oxygen and subsequent combustion in the chamber 7.

Many arrangements, of course, may be used for regulating the introduction of liquid oil into the trough 9. However, in the form of the invention illustrated, the burner is of simplified design and is adapted for use in the heating of water in connection with various farm activities. Simple, effective and reliable apparatus for regulating the flow of oil is thus indicated. A pipe line 10 is, therefore, provided which leads from an elevated oil-supply drum, not shown. In the line 10, there is a shut-off valve 11 of the manually operated type. Threadedly carried by one of the casing walls 2 is a horizontal valve body 12 having an internally threaded bore 13 in which is received the correspondingly threaded end of a second oil-supply pipe 14 which also extends from the oil-supply drum. The bore 13 terminates in a reduced extension 15, and in this extension there is arranged a thermostatic valve stem 16.

One end of the valve stem 16 has an adjustable threaded connection 17 with one of the casing walls 2, so that the valve stem projects horizontally across the combustion chamber 7 below the ledge 8, as shown in Fig. 2. Also, the stem 16 passes through the opposite wall 2 of the burner casing and through a packing 18, the latter being positioned in the threaded end of the valve body 12 positioned in a socket 19 formed in the wall 2 which carries the body 12. The outer end of the thermostatic stem 16 is provided with a head 20 which normally engages with a seat 21, formed at the juncture of the reduced extension of the bore 13 with the enlarged outer threaded portion therefor. The stem 16 is formed from a metal which expands more rapidly under the influence of heat than the metal or metals from which the casing 1 or the valve body 12 is formed, with the result that whenever the valve stem is materially heated above normal atmospheric temperatures, the head 20 of said stem expands beyond the seat 21, thus opening the seat and allowing oil to flow through the valve body 12 from the pipe 14.

When the operation of the burner is initiated, the valve 11 is manually opened, so that oil flows

from the source of supply through the pipe line 10 and thence into the valve body 12 by way of the vertical port 22. Since the head 20 is seated at the time when operation of the burner is initiated, the oil then passes around the stem 16 and into an outlet port 24 arranged in vertical registration with and below the inlet port 22. The oil then flows under the action of gravity, or by suitable pressure means, if used, through a substantially U-shaped pipe line 24a, which passes under the casing 1 and is joined with a needle valve body 25, the latter having threaded connection with one of the side walls 2 of the casing and enters the well or trough 9, as indicated in Fig. 3. The needle valve is indicated at 26 and is adjustably mounted in the body 25. Adjustment of the valve 26 may be effected by manual rotation of its key-shaped end 27. It will be seen that with the valve 11 open, oil flows through the valve body 12, the pipe line 24, the needle valve 26 and into the bottom of the trough 9.

Arranged in the bottom of the well 9 is a number of corrugated or crimped wires 28, disposed in loosely packed order, as shown in Fig. 3. Above these wires, the trough may be packed with alternate layers of asbestos and metal screen bars, as indicated at 29. Also, the outer wall of the trough 9 has positioned around the same an inverted U-shaped capillary screen wick 30, which serves to remove oil from the bottom of the trough 9 and to facilitate its vaporization and union with air to form a combustible mixture within the chamber 7.

The top of the combustion chamber 7 is normally protected by a removable cover 31. The vertical side walls of this cover are notched as at 32 for the reception of lugs 33 projecting from the outer surfaces of the side walls 2. The curved front and rear walls of the cover 31 are thus spaced from the corresponding walls of the casing 1 to form a primary air inlet, so that atmospheric air may be drawn into the top of the chamber 7.

In order to control the inflow of the primary air entering the chamber 7 from the top of the latter, an adjustable apertured air distributing plate 34 is provided. This plate is arranged at a slight angle with respect to the horizontal and rests upon inclined shoulders 35 projecting inwardly into the chamber 7 from the vertical sides of the walls 2. The lower portion of the plate 34 is formed with a plurality of spaced longitudinally extending rows of apertures 36, and above these apertures, the plate 34 is integrally formed with a hood 37, producing a restricted air flow slot or chute 38 above the apertures 36. This air distributor may be adjusted relative to the ledge 8 by the provision of a screw 39, the shank of which engages at one end with a shoulder 40 at the upper edge of the baffle wall 6.

The cover 31 and the air distributor 34 are readily removable from the burner to provide access to the oil-receiving trough 9. Thus when the operation of the burner is first started, the cover 31 and the air distributor 34 are removed, so that a torch, or other flame, may be applied to the open top of the fuel well or trough 9, providing for the vaporization of the liquid oil within the bottom of the trough and its subsequent combustion. After this pilot combustion has been initiated, the air distributor 34 is restored to its normal operating position, as is the cover 31. Following a brief interval of this pilot operation, 75

the valve 11 may be closed, since the thermostatic stem 16 becomes sufficiently heated and expanded so that its head 20 is separated from the seat 21 to provide for the required oil flow through the line 14 to the burner. Thus, if, for any reason, the burner should be accidentally extinguished, the thermostatic stem 16 will again seat to arrest oil flow to the burner and overcoming oil flooding of the burner. With the stem 16 expanded, a sufficient quantity of oil is allowed to flow into the bottom of the trough for vaporization purposes. The vaporized oil ascends through the surface extending members formed by the wires 28, the bars 29 and the screen 30, the normal heat of the burner being such as to vaporize the oil so that it may readily combine with atmospheric oxygen introduced into the chamber 7 by the regulated flow of air through the apertures 36 of the air distributor 34. The amount or quantity of air, however, introduced through the plate 34 is of insufficient volume to secure efficient combustion and, therefore, secondary air is admitted into the chamber 7 for union with the combustible mixture by way of a secondary air passage 41. If desired, the passage 41 may be equipped with a valve or damper 41a for regulating the amount of air passing therethrough. The passage 41 enters the chamber 7 toward the bottom of the latter and well spaced from the source of admittance of the primary air, this feature being attained by the inclusion of the wall 6.

When this improved burner is used to heat water or the like, the products of combustion or burning gases leaving the outlet 42 of the chamber 7, are passed through a flue 43 formed by a water-containing jacket 44, the latter being detachably connected as at 45 with the burner casing. If the flue 43 is of considerably greater diameter than the outlet 42, openings 46 may be provided to admit limited quantities of tertiary air into the burner to effect complete combustion of the fuel mixture.

In view of the foregoing, it will be seen that the present invention provides a simple and efficient hydrocarbon burner which operates with the use of a natural draft, produces a rapid short flame and utilizes kerosene or furnace oil as a source of fuel. The burner may also operate with the use of gaseous hydrocarbon fuels. The flame produced within the combustion chamber of the burner is completely enclosed, and back drafts, passing through the burner will not cause flame combustion to take place exteriorly of the burner casing. Liquid fuel is fed to the burner by gravity under uniform flow conditions, and not by drops or similar intermittent or interrupted flow. By getting the fuel into the bottom of the well 9, the burner operates with a very low and regular flame. Also the shape of the well, and the inclusion of the wick device therein, provides a uniform generation of vaporized fuel throughout the width of the well, thus greatly assisting in the generation of gas and the mixing of the gas with air.

The perforated air distributing plate 34 is so situated as to prevent the flame, created within the chamber 7, from traveling upwardly or escaping from the top of the burner. It will be observed that this plate is slidably adjustable over the vaporizing well at an angle thereto. When adjusted back and forth, the space between the top of the well and the plate is varied to meet the capacity requirements of the burner. Thus when the burner is in operation, primary

air entering the top of the burner passes downwardly and around the end of the plate, forcing the gas over and under the perforated lower side of the plate, where the fuel mixture is ignited. The openings in this plate are of such size as to cause the fuel to burn vigorously directly under the plate. When operated in this manner, visible flame combustion is observable immediately beneath said plate.

The burner is preferably operated with a short flame, which is created in the combustion chamber 1 immediately to the front of the fuel-receiving well, and the air supplied to the combustion chamber through said plate and by means of the secondary air inlet 41 is adjusted in volume to establish this zone of combustion. When properly adjusted, a long flame extending into the flue 43 is avoided and, likewise, soot and carbon deposit is minimized. The fuel vaporizing well is located in such position that the flame passes along one side of the well and under its bottom, thus supplying the necessary heat to vaporize or gasify liquid fuels introduced into the bottom of the well. The back side wall of the well is spaced from the wall 5 of the burner casing so that the heat of combustion may be efficiently applied to the back of the well, in addition to the front and bottom thereof. The back wall of the well is joined with the wall 5 of the casing by the horizontal ledge 8. Since this ledge is solid and unperforated, it causes air, entering by way of the primary inlet, to pass around the lower portion of the air distributing plate and over the open top of the fuel well, thus preventing the burning of oil immediately over the open top of the well and providing for proper admixture of air with the vaporized fuel before flame combustion takes place. The amount of air flowing over the open top of the well may be varied by adjusting the air distributing plate toward and away from the ledge 8. The burner is devoid of small delicate parts, such as jets or the like which are apt to become out of order or to occasion frequent adjustment or repair.

In order to clean the burner, it is merely necessary to remove the screws or bolts 45, which detaches the burner casing from the water heating jacket or manifold 44. The cap or cover may then be lifted from the casing and the plate 34 removed, thus providing convenient access to the interior of the burner, as well as the manifold or jacket 44.

What is claimed is:

1. A hydrocarbon burner comprising a casing having an internal combustion chamber, an open-topped fuel-receiving well extending transversely and horizontally across said chamber between the top and bottom thereof, a primary air inlet entering said chamber above said well, a perforated air distributing plate positioned in said chamber and extending substantially across the same between said air inlet and the top of said well, a secondary air inlet entering said chamber below said well, and an outlet for gaseous products of combustion disposed below said well and on the opposite side of said well from said secondary air inlet.

2. A hydrocarbon burner comprising a casing formed with an internally disposed combustion chamber, a primary air inlet entering the top of said chamber and a secondary air inlet communicating with the lower portion of said chamber, an open-topped fuel-receiving well stationarily positioned in said chamber and extending transversely across the same between the primary and

secondary air inlets, a perforated air distributing plate positioned in said chamber and extending substantially across the same above the open top of said well, said plate providing for a controlled flow of air from said primary inlet into said chamber with a portion of the air so admitted traveling across the open top of said well, and an outlet for burned gases provided in the lower portion of said casing substantially below said well and on the opposite side of said well from said secondary air inlet.

3. A hydrocarbon burner comprising a casing formed with an internal fuel vaporizing and combustion chamber, a primary air inlet entering the top of said chamber, a secondary air inlet entering said chamber contiguous to its bottom, a substantially U-shaped fuel-receiving well stationarily mounted within said chamber between said primary and secondary air inlets, the front, back and bottom walls of said well being spaced from the corresponding walls of said chamber, means for admitting fuel into the bottom of said well in regulable quantities, a perforated air distributor arranged in said chamber between said primary air inlet and said well, said distributor being adjustable to vary the quantity of air admitted and serving to effect a flow of air across the top of said well to produce a combustible fuel mixture, and an outlet for gaseous products of combustion leading from said chamber contiguous to the bottom thereof and on the opposite side of said casing from said secondary air inlet.

4. In a hydrocarbon fuel burner, a casing having a normal fuel mixing and combustion chamber, primary and secondary air inlets entering the top and bottom of said chamber, respectively, a fuel-receiving and vaporizing cup stationarily positioned in said chamber between said air inlets, a perforated air-admitting plate extending transversely across said chamber and disposed between said primary air inlet and the top of said cup, guides in which said plate is mounted for sliding adjustment, threaded means cooperative with said plate for adjustably spacing the inner portion of said plate relative to said cup, and an outlet for gaseous products of combustion leading from the bottom of said chamber in spaced relation from said secondary air inlet.

5. In a hydrocarbon fuel burner, a casing having a normal fuel mixing and combustion chamber, primary and secondary air inlets entering the top and bottom of said chamber, respectively, a fuel-receiving and vaporizing cup stationarily positioned in said chamber between said air inlets, a perforated air-admitting plate extending transversely across said chamber and disposed between said primary air inlet and the top of said cup, guides in which said plate is mounted for sliding adjustment, threaded means cooperative with said plate for adjustably spacing the inner portion of said plate relative to said cup, an outlet for gaseous products of combustion leading from the bottom of said chamber in spaced relation from said secondary air inlet, and a removable cover element carried by the top of said casing.

6. In a hydrocarbon fuel burner, a casing having a combustion chamber extending longitudinally thereof, said chamber having an outlet at one end, primary and secondary air inlets communicating with said combustion chamber at the top and one end respectively, a fuel receiving and vaporizing trough extending transversely of said combustion chamber between said inlets and the outlet, the open upper portion of said trough being disposed adjacent to the primary air inlet,

and air controlling means disposed in said primary and secondary air inlets, the air controlling means in said primary air inlet having a pair of plates supported in spaced relation, the plate nearest to said trough having a plurality of spaced perforations for the introduction of primary air to said burner.

7. In a hydrocarbon fuel burner, a casing having a combustion chamber extending longitudinally thereof, said chamber having an outlet at one end, primary and secondary air inlets communicating with said combustion chamber at the top and one end respectively, a fuel receiving and vaporizing trough extending transversely of said combustion chamber between said inlets and the outlet, the open upper portion of said trough being disposed adjacent to the primary air inlet, air controlling means disposed in said primary and secondary air inlets, the air controlling means in said primary air inlet having a pair of plates supported in spaced relation, the plate nearest to said trough having a plurality of spaced perforations for the introduction of primary air to said burner, and means for moving

5 said plate relative to said casing to provide for the flow of air between the edge of said plate and the wall of said casing, the air thus admitted flowing over the open top of said trough.

8. In a hydrocarbon fuel burner, a casing having a combustion chamber provided with an outlet, an air inlet passage communicating with said chamber from the top, a fuel receiving and vaporizing trough extending transversely of said air inlet passage adjacent to the side nearest the outlet of said combustion chamber, an air controlling and distributing member extending across the open upper end of said air inlet passage, said member having a plurality of spaced perforations, and means for adjusting said member to provide for a flow of air into said passage at one side of said trough, said air flowing over the open top of said trough to mix with vapors arising therefrom to produce a combustible mixture, the products from combustion of the mixture flowing downwardly around and under said trough to the combustion chamber outlet.

MERLIN E. PALSGROVE.
